UNITED STATES PATENT OFFICE.

ALFRED HERMAN KOELLER, OF NEW YORK, N. Y.

CAR-FENDER.

SPECIFICATION forming part of Letters Patent No. 537,211, dated April 9, 1895.

Application filed September 11, 1894. Serial No. 522,702. (No model.)

To all whom it may concern:

Be it known that I, ALFRED HERMAN KOELLER, a citizen of the United States, residing in the city and county of New York, in the 5 State of New York, have invented a certain new and useful Improvement in Car-Fenders, of which the following is a specification.

The improvement is intended for cars which run singly or in small trains on the streets of 10 cities, and in analogous situations, impelled by cable or by other means as by electricity. It belongs to that class in which an extended net or other receptacle is provided in front of the end of the car to receive any person or 15 object which shall be struck and preserve it from serious injury. There have been many efforts in this line.

The necessity for traversing curves requires 20 that the ordinary supporting wheels of the car shall be near the mid-length. The unavoidable irregularities in the track impart motions to the car which are liable to be increased by the action of the springs, and such cars are especially liable to a pitching motion 25 which will raise and lower the ends several inches.

My invention provides for mounting the fender on the car end and yet allowing it to travel with practical uniformity at a little 30 height above the track.

The fender is formed with an arm at each side which is connected to the car by a universal joint so that it can allow the front end to rise and sink as far as is ever required in 35 practice, and also to be deflected to the right and left to the considerable extent required in traversing ordinary moderate curves on the road. A cross-bar loosely connects the front ends of these arms and carries small 40 wheels specially adapted to endure the conditions, and having each a flange corresponding to the flanges of the large wheels, which traverse on the rail and control the position of the front of the device. The car may pitch 45 forward and backward, and roll and turn partially from side to side, without materially disturbing the front edge of the fender.

I make the fender light, and adapted to be easily transferred from one car to another, or 50 from one end to another of the same car, when

such change becomes necessary. I provide for holding down the small wheels reliably upon the track by springs peculiarly mounted. I provide means for lifting the front edge and holding the small wheels clear of the track 55 whenever required.

The accompanying drawings form a part of this specification and represent what I consider the best means of carrying out the invention.

Figure 1 is a side elevation of the invention applied to a car. Fig. 2 is an end view seen from the left in Fig. 1. Fig. 3 is a plan view with the roof of the car removed. Fig. 4 is a plan view of the same part seen from below. 65 In all these figures the universal joint is shown as formed by a rounded hook on the lever dropped into a rounded eye on the car platform. Fig. 5 is on a larger scale. It is a horizontal section through one of the small 70 bearing wheels with a plan view of the adjacent portion of the cross-bar on which the wheel is allowed to turn loosely by the aid of anti-friction balls. Fig. 6 is a plan view of a portion on a larger scale; and Fig. 7 is a vertical cross section.

Similar letters of reference indicate corresponding parts in all the figures where they appear.

A is the main body of the car; A', the platform; A², the dash-board or front; A³, one of the cross timbers or bolsters of the car, and A⁴ arms extending rigidly downward near the end of the car.

B, B, are the ordinary supporting wheels of 85 the car. They are, as usual, fast on their axles, B', and carried in boxes C supplied with lubricating material, with liberty to move up and down in jaws A⁵, and support the car-body by means of springs D, constructed and arranged in any ordinary or suitable manner.

M, M, are levers provided each with a short rounded hook or arm M', by which it may be engaged in a pocket or socket a in the front end of the car, one on each side.

P is a cross-bar connecting the front ends of the levers M by the aid of bolts and nuts P', P², and provided with bearings P³ and nuts P⁴ adapted to form by the aid of the rolling balls Q reliable anti-friction bearings for small 100

wheels R, having relatively large flanges R', and adapted to traverse lightly but reliably on the track, one wheel on each rail.

T, T, are contractile springs of steel or other suitable material, each connecting an eye M² on the under side of a lever M with an arm A⁴. The arrangement makes these springs act very efficiently to hold the wheels R' down upon the track while running, but when the fender is lifted the angle at which the springs act being changed they relax the force so that a slight force will hold the fender elevated.

The net or screen E extends across with a little slack between the lever M and the front cross-bar P and the dash-board or front A² of the car. Any person or object struck by the car in rapid motion is tripped by my device and caught on the net E and retained until the car can be stopped. When the car tilts or pitches forward and backward, the levers M yield vertically. When the car twists to the ordinary small amount experienced in practice, or traverses a curved portion of the road, the levers M turn laterally to accommodate such motion.

It is important to provide means for elevating the fender so that the wheels R and their flanges R' shall be entirely clear of the track, when necessary, as in passing certain switches and abrupt curves. The driver or motor-man effects this when required by a vigorous action of his foot.

W is a treadle playing through the platform A', and having an extended top, which under ordinary conditions stands several inches or a foot above the platform. It connects to a V-shaped lever Y, pivoted at two widely separated points on the bolster A³ and bearing on a cross-bar N which is loosely connected at each end to a rearward extension M³ of a lever M. Under ordinary conditions the superior gravity of the forward portion of the device, aided by the considerable force of the springs

T, while the fender is depressed holds the wheels R down upon their respective rails and insures that the front edge of the net E is supported at the small distance above the track required for successful working. Under these conditions the bar N is carried high, and the lever Y and treadle W are held in a correspondingly high position, the smooth upper surface of the bar N playing to the right and left under the two bearing points of the V-shaped lever, in the obvious manner, to accommodate the lateral movements of the levers M due to the irregularities of the motions or the curves of the track. When an occasion arises for elevating the fender, the attendant throws his weight upon the treadle W, depressing the lever Y and consequently the cross-bar N, and raising the front of the fender so that the wheels are clear of the track. The bearings of the lever Y on the bar N insure that the depression of the two ends of the

bar shall be substantially equal, and consequently that the two wheels R and the whole front of the device shall be raised with practical uniformity from one side across to the other. The changed angle at which the springs T exert their tension greatly reduces the effect at these periods. Thus conditioned, the car may travel over obstacles or over a switch, or the greatly curved portions of the track which occur at the entrance to the car-house.

The pockets a may be iron. They form with the rounded ends of the arms M' universal joints for allowing the levers M to be deflected to a sufficient degree in all directions,—up, down and sidewise. The gravity of the levers M and their attachments aided by the tension of the springs T holds each projection M' always reliably engaged in its pocket or socket a.

Whenever it shall be necessary to disconnect the principal parts of my invention and put them out of use, or transfer them to another car, or to the other end of the same car, I detach the fastenings which hold the net E to the dash-board A², and detach the rear ends of the springs T from the rigid arms A⁴. Now on lifting the levers M sufficiently to detach the arms M' from the pockets a, all the removable parts are clear of the car.

I allow the V-shaped lever Y to remain, and provide a pin A⁶ shown in strong lines in Fig. 4, and in dotted lines in Figs. 1 and 3,—to support it. These pins reach inward toward the center line of the track from each arm A². They are of no effect except when the main portion of my mechanism is removed and it is required to simply hold up the V-shaped lever Y and keep it clear of the ground, until the apparatus shall be again restored to a working condition.

The treadle W may be allowed to remain. When not required it may be lifted out of its socket and stored in any convenient place until wanted.

Modifications may be made in the details. The rear end of the net E may be wider so as to reach considerably outside of the lever M.

I claim as my invention—

1. In a car-fender, a net supported at the sides by levers turning on universal joints carried on the car, in combination with flanged wheels running on the rails at the front of the fender, and with springs extending longitudinally and connecting to arms A⁴ extending downward from the car body, arranged to depress the levers to hold the wheels upon the track with a force which is diminished with the elevation of the fender, and with provisions for lifting the front edge at will, all substantially as herein specified.

2. In a car-fender, a net supported at the sides by levers turning on universal joints, carried on the car, in combination with flanged wheels running on the rails at the front of the fender, and with springs at the rear ar-

ranged to depress the levers to hold the wheels upon the track, and with the treadle W, arranged to be depressed by the attendant, the lever Y operated thereby and the cross-bar N loosely connected to rearwardly extending arms of the levers, adapted to allow the fender to be raised both sides alike, all substantially as herein specified.

In testimony that I claim the invention above set forth I affix my signature in presence of two witnesses.

ALFRED HERMAN KOELLER.
